SHEARING MACHINE

Robert T. Hazelton, Cincinnati, Ohio, assignor to
 The Cincinnati Shaper Company, Cincinnati,
 Ohio, a corporation of Ohio

Application May 4, 1933, Serial No. 669,399

7 Claims. (Cl. 164—47)

My invention relates to shears of a type in which there is a stationary shear knife and a movable shear knife attached to a ram which is actuated by pitmen. Hitherto it has been impracticable to use shears for certain kinds of slitting operations, because if the knives pass each other at the end of a stroke the piece will be notched or split at the end of the cut, which makes it impossible to do clean, continuous slitting. It is possible to do clean, continuous slitting if the movable knife is made adjustable at least as to the position of its stroke, so that at the end of the stroke there will be a portion of cutting edge of the movable knife extending above the fixed knife. In this way notching may be prevented, and a splitting of the piece, as will hereinafter be explained. Under some circumstances a notching of the piece is desirable, but this again calls for a very careful adjustment of the position of the stroke. My invention is addressed to means for securing such adjustability in the position of the stroke of shear knives, and the general and specific objects thereof will be pointed out hereinafter or will be apparent to one skilled in the art upon reading these specifications.

Reference is now made to the drawings, wherein:

Figure 1 is an elevational view with parts in section of an exemplary shear embodying my invention.

Figure 2 is a sectional view of a portion of the adjustment device.

Figure 3 is a view of another portion of the adjustment device.

Figure 4 is a sectional view of a simpler form of adjustment device.

Figure 5 is a sectional view of a housing member employed in connection with the device shown in Figure 1.

Figures 6 and 7 are views in section and end elevation respectively, of the clamping device employed in the embodiment of Figure 1.

Figure 8 shows the eccentricity of the eccentric pin, and Figure 9 shows the pin in plan, meshing with a pinion on the controlling shaft.

Figure 10 shows a clean slitting cut.

Figure 10a shows the relative positions of the knives at the end of said cut.

Figure 11 shows a notched slitting cut.

Figure 11a shows the knives at the end of the cut of Fig. 11.

Figure 12 shows a split slitting cut.

Figure 12a shows the knives at the end of the cut of Fig. 12.

Figure 13 shows one of the pitmen.

Figure 14 indicates the housing of one of the controlling devices mounted upon the ram.

In making the ordinary shearing cut, the knives pass each other so as completely to sever the piece, unless the piece extends out beyond the ends of the knives. If an attempt is made to use a shear so adjusted in a slitting operation, a cut is made like that indicated in Figure 12 in the piece 1, where 2 indicates a slitting cut, 5 and 3 indicates a split at right angles, or a deformation produced in the piece at right angles to the slitting cut. Obviously this split precludes the production of two perfect pieces from the piece 1. If the knives are so adjusted that 10 the cutting edges thereof do not pass throughout their entire length, then a cut is produced like that shown in Figure 11 in the piece 1, where 4 indicates a notch at right angles to the line of slitting cut. Under some circumstances, such 20 a notching of the piece is desirable, particularly if such a notch denotes the point at which the portion 5 is to be cut off in Figure 11. However, in many instances continuous slitting is desirable, the purpose being to sever a piece longer 25 than the cutting edges, respectively, of the knives into two pieces by dividing it longitudinally. Under such circumstances a clean slit like that shown in Figure 10 is desirable, where in the piece 1 there is merely the slitting cut 2 without 30 either a notch or a split. The piece 1 in Figure 10 may be advanced longitudinally of the knife and subjected to further slitting operations, making therein a clean and continuous cut. It is an obvious fundamental object of my invention to 35 provide in power operated shears a means for adjusting the position of the stroke so as to produce any desired type of cut in the metal piece, and still more specifically to provide a shear which may be selectively used to produce a severing cut, or any type of slitting cut indicated herein.

I have shown in Figure 1 a shear in which a frame member is indicated at 6. The shear table is shown at 7, bearing the stationary knife 8. 45 A movable knife 9 is mounted on a ram 10, which moves against machined guiding surfaces 11 on the frame member 6. Pitmen are provided, indicated at 1a, and shown in detail in Figure 13. These pitmen have a machined orifice 12 to fit 50 over the usual eccentric on the main driving shaft 13. The pitmen also have a machined orifice 14 to fit over a pin attached to the ram 10. It will be understood that suitable bearings are employed, and also that as the pitmen are drawn 55

downwardly they move the ram 10 downwardly. The ram may have attached to it brackets 15, supporting a back gauge mechanism with parts indicated generally at 16. In order to keep the ram back tightly against the machined guide surfaces 11, a spring device indicated generally at 17 may be provided attached to the frame of the device, and provided with a tensioned rod 18 attached to the brackets 15. This also furnishes the counterbalance for the ram.

My invention contemplates adjusting the stroke of the ram 10 by varying the position of the center of engagement of the ram and the pitmen, and to this end I have provided a pin for each pitman, journaled on the ram and having a portion which is eccentric, that portion being the part which is engaged by the pitman.

In the simplest form of my device shown in Figure 4, these pins are part of a shaft 19, provided with shoulders, or the like 20, whereby the shaft may be engaged by a wrench and turned. The shaft 19 is continuous across the top of the ram, and provides for the simultaneous adjustment of the stroke with respect to each pitman.

The shaft 19 at its ends bears the pins aforementioned, one of which is indicated in Figure 4 at 21. This pin is journaled as at 22 and 23 in a housing member 24, fixed by means of bolts 25 or otherwise to the ram 10. The top of the pitman is indicated at 1a in Figure 4, and is shown engaging a portion 26 of the pin 21, which portion is eccentric. The end of the pin 21 is flattened as at 27 and 28, and may therefore be adjusted to two positions indicated by suitable indicia 29 on a visible portion of the pin 21. A clamping device 30 is arranged to be held against the flattened portion of the pin by means of a nut and stud 31. By loosening this nut, the shaft 19 may be engaged at its portion 20 by a wrench, rotated a half turn and clamped in its new position. While Figure 4 indicates the pin and associated construction upon one end of the shaft 19, it will be understood that for the other pitman, or for any number of pitmen by which the ram is engaged, there will be pins which are the counterpart of that shown. Moreover, it will be understood that a rotation of the shaft 19 will turn all of the pins in unison, thereby providing for the concurrent, simultaneous and accurate adjustment of the stroke of the ram with respect to each pitman.

In the device of Figure 4 I have provided for two positions of the shaft 19 called "up and down". In the "up" position, the position of the stroke of the ram is so adjusted that the knives of the shear pass each other throughout part only of their length. In the "down" position, the stroke is such that the knives pass each other throughout their length, i. e. the stroke is the normal shearing stroke.

With respect to the two positions aforesaid, the two alternative centers for the point of application of the pull to the ram are directly in line with the direction of pull applied to the ram by the pitman. So long as this condition obtains, the clamping means shown in Figure 4 are adequate to maintain the eccentric of the pin 21 in a fixed position with respect to the ram. Where greater adjustability is desired, a different construction is preferable, since the expedient of flattening the end portion of the pin 21 gives only a limited range of adjustability, and if greater adjustability is desired, would not provide a satisfactorily rigid construction. Moreover, while I have shown in Figure 4, the shaft

19 as passing over the top of the ram, in the larger shears the ram has to be crowned to make it rigid, a portion of which crown is shown at 10a in Figure 14. This crown in many instances would prevent the passage of the shaft 19 directly over the top of the ram.

In the construction shown in Figure 1 and detailed in Figures 2, 3 and 5 to 9, I have shown a modified form of my invention, wherein the common operating shaft for the adjustment is not attached directly to the pins, but operates the pins by means of a gear arrangement.

Referring now to Figure 2, I have shown a pin indicated at 21a, journaled in a housing 32, bolted as at 33 to the ram 10. The eccentric portion of the pin is indicated at 26a, and is shown engaging the pitman 1a. A portion 34 of the pin is provided with gear teeth. The pin may be rotated by a gear, hereinafter to be described, engaging these teeth; and the pin may be held in whatever position is selectively chosen, by means of a clamping member 35 held by a nut and stud 36, and provided in its portion 37 with teeth to engage the teeth of the gear 34 on the pin. This clamping member is shown in greater detail in Figures 6 and 7, where like parts are indicated by like numerals, and the teeth on the clamping member are indicated at 37a. The clamping member may be provided with a coil spring 38, which will tend to raise it out of engagement with the gear 34 when the nut 36 is loosened. It will be clear that this construction permits the adjustment of the pin 21a to a plurality of positions, and the positive clamping of the pin in any one of these positions by means of the member 35. The number of such positions will be determined by half the number of teeth on the gear member 34, since this member makes but half a revolution for the whole cycle of adjustment. By this arrangement I secure a construction which is rigid against strains, even when the center of engagement of the pitman and the ram lies to one side of a line representing the direction of pull of the pitman on the ram. The pin is shown in detail in Figures 8 and 9, where like indicia indicate like parts. The toothed portion 34a not only is used for clamping purposes, but is used in rotating the pins by means of a gear 39, which is non-rotatably attached to the shaft 19a. By reason of this arrangement of parts, the shaft 19a may be offset from the face of the ram so as to pass the crown thereon. I have shown in Figure 3 the shaft 19a bearing a portion 20a for engagement by a wrench, and also bearing the pinion 39 which meshes with the portion 34 of the pin. The shaft 19a is mounted in a housing member 40, which is preferably cut away as shown at 41 in Figure 14 to expose a portion of a collar 42 on the gear 39, which may be provided with indicia 43 to indicate, in conjunction with a zero line 44 on the housing 40, the position of the pins, and hence the adjustment of the shear stroke.

In this way I have provided for the positive and substantially continuous adjustment of the stroke of a shear to provide for a number of different operations. I have provided also for the concurrent adjustment of all points of engagement of the ram with any of the pitmen. It will be obvious that modifications may be made in my invention without departing from the spirit thereof.

Having thus described my invention, what I claim as new and desire to secure by Letters Patent, is:—

1. In a power shear having a fixed knife, the combination of a ram bearing a movable knife, pitmen for actuating said ram, and means for adjusting the position of the stroke of said ram, 5 said means comprising eccentric members attached to said ram and engaged by said pitmen respectively, and concurrently acting means for rotating said eccentric members to vary the position of the center of attachment of said pitmen 10 to said ram, said concurrently acting means comprising a separately mounted shaft offset from said eccentric member and having a driving connection therewith.

2. In a power shear having a fixed knife, the combination of a ram bearing a movable knife, pitmen for actuating said ram, means for adjusting the position of the stroke of said ram, said means comprising eccentric members attached to said ram and engaged by said pitmen 20 respectively, concurrently acting means for rotating said eccentric members to vary the position of the center of attachment of said pitmen to said ram, said means comprising a shaft arranged to rotate all of said eccentric members, 25 and means for positively and directly retaining said eccentric members in a plurality of positions selectively.

3. In a shear having a ram and pitmen, means for adjusting the position of the stroke of said ram comprising a plurality of pins journaled on said ram and having eccentric portions for engagement with said pitmen, a portion of each of said pins being provided with gear teeth, and non-rotating clamping means also provided with 30 gear teeth for engagement with said first mentioned teeth for clamping said pins fixedly in a plurality of selected positions.

4. In a shear having a ram and pitmen, means for adjusting the position of the stroke of said ram comprising a plurality of pins journaled on said ram and having eccentric portions for engagement with said pitmen, a portion of each of said pins being provided with gear teeth, clamping 40 means also provided with gear teeth for en-

gagement with said first mentioned teeth for clamping said pins fixedly in a plurality of selected positions, a shaft common to said pins and provided with pinions for meshing with the toothed portions of each of said pins, and means whereby said shaft may be rotated to rotate all 5 of said pins in unison.

5. In a shear having a ram and pitmen, means for adjusting the position of the stroke of said ram comprising a plurality of pins journaled on said ram and having eccentric portions for engagement with said pitmen, a portion of each of said pins being provided with gear teeth, clamping means also provided with gear teeth for engagement with said first mentioned teeth for 15 clamping said pins fixedly in a plurality of selected positions, a shaft common to said pins and provided with pinions for meshing with the toothed portions of each of said pins, means whereby said shaft may be rotated to rotate all 20 of said pins in unison, and indicating means for indicating the position of said pins.

6. In a shear having a ram and pitmen, means for varying the position of the stroke of said ram, comprising a plurality of pins journaled on said 25 ram and having eccentric portions for engagement with said pitmen, and a common shaft having a driving connection with all of said pins located in a position offset from the face of said ram, and means for clamping said pins in a plurality 30 of selective positions.

7. In a shear having a fixed knife, a ram, a movable knife attached to said ram and pitmen for operating said ram, means for adjusting the position of the stroke of said ram to produce 35 selectively a severing cut or a slitting cut, said means comprising means for varying the center of engagement of said pitmen and said ram to different positions for each of said types of cut, said adjustment being such that in each of said 40 positions the centers of engagement of said pitmen and said ram coincide with a line representing the direction of pull of said pitmen.

ROBERT T. HAZELTON.
